UNITED STATES PATENT OFFICE.

ISAAC W. HOFFMAN AND PETER K. EBERSOLE, OF ELIZABEHTOWN, PENNSYLVANIA.

NUT-LOCK.

SPECIFICATION forming part of Letters Patent No. 738,539, dated September 8, 1903.

Application filed March 27, 1903. Serial No. 149,812. (No model.)

To all whom it may concern:

Be it known that we, ISAAC W. HOFFMAN and PETER K. EBERSOLE, citizens of the United States, residing at Elizabethtown, in the county of Lancaster and State of Pennsylvania, have invented certain new and useful Improvements in Nut-Locks; and we do hereby declare the following to be a full, clear, and exact description of the invention, such as will enable others skilled in the art to which it appertains to make and use the same.

This invention relates to improvements in a nut-lock of that class especially adapted to the securing of the nuts on the bolts of railway-rail joints in which a plate or strap with side notches or recesses therein is placed over the nuts, so that they will lie or engage in said notches or recesses, preventing said nuts from turning; but the invention relates more particularly to the means provided for removably securing said plate or strap in nut-locking position.

The object of the invention is to provide the nut-locking plate or strap with spring-actuated bolts, whereby said plate or strap will be securely held in nut-locking position, and to be removed from said position when said nuts will have to be either tightened, loosened, or removed; and a further object of the invention is to extend the scope of that patented to Peter K. Ebersole in No. 716,395 on December 23, 1902.

The elements of the invention will severally and at large appear in the following description, and they will be separately or combinedly set forth or pointed out in the appended claims.

The purposes of the invention are attained by the mechanism, devices, and means illustrated in the accompanying drawings, with similar reference characters to designate like parts throughout the several views, in which—

Figure 1 is a side elevation of a railway-rail joint with a nut-locking plate or strap embodying the elements of the invention in position thereon. Figs. 2 and 3, respectively, are elevations of the left and right hand ends of Fig. 1. Fig. 4 is a sectional elevation taken on the line $x-x$ in Fig. 1 viewed from the right; Fig. 5, a cross-sectional plan, longitudinally

arranged, of the portion below the line $y-y$ in Fig. 3. Figs. 6 and 7 are enlarged sectional plans, centrally taken, of the left and right hand end portions of the locking-plate or strap, showing the securing-bolts in locked positions with an unlocking-tool in place at the outer end of each bolt; and Figs. 6^a and 7^a similar plans of the same portions, showing said bolts in unlocked positions. 60

In the drawings, A designates the contiguous ends of two railway-rails; A', the fish-plates placed against the webs of said rails and covering their bases; A², the bolts passed through the fish-plates and rail-webs, and A³ the nuts on the threaded end of said bolts and screwed home onto the adjacent fish-plate, thus completing the usual rail-joint. Four bolts are here shown; but this number is not limited. 70

Thus far nothing new has been shown or disclosed; but one object of this invention is to provide simple and secure locking means preventing the nuts from turning on their bolts; and a second object of the invention is to removably secure said locking means. 75

First, then, to prevent the nuts from turning on their respective bolt ends a plate or metal strap B of the required dimensions is provided through its body with notches or recesses b, adapted to engage on or about said nuts, said strap lying close to or engaging against the forward surface of the adjacent fish-plate and having its ends b' b² projecting beyond the extremities of said fish-plate, said ends to support the securing and releasing bolts with their springs. The right-hand end b', being in prolongation of the body of said strap, has at its outer extremity an abrupt offset or rearwardly-extending perpendicular wall b³, the rearward edge thereof contacting with the rail-web and having therein a circular bearing-orifice b⁴, while at a prescribed distance from the right-hand end of the fish-plate, on the inner surface of this end b', is arranged a staple b⁵, provided with an angular aperture b⁶ and rigidly secured in place, as by being riveted to the strap. At a prescribed distance from the left-hand end of the fish-plate, in the left-hand end portion b² of the strap, is formed a rearwardly-extending perpendicular offset or wall b⁷, the 95 100

rearward edge thereof contacting with the rail-web, along which it extends a prescribed distance and thence forwardly in a perpendicular wall b^8 , having therein a circular bearing-orifice b^9 , while the wall b^7 is provided with an angular bearing-aperture b^{10} . Between the staple b^5 and the wall b^7 and the adjacent extremities of the fish-plate are prescribed recesses $b^{11} b^{11}$, constituting clearance-spaces for the head ends of bolts yet to be described, said staple b^5 , with the walls b^8 , b^7 , and b^8 through their bearings, supporting said bolts.

Through the bearings of the extensions $b' b^2$ of the strap B are mounted bolts C C', exactly similar in form but oppositely disposed, having angular heads c, respectively engaging in the apertures $b^6 b^{10}$, the former of the staple b^5 and the latter of the wall b^7 , said heads having side projections c' to engage against the rail-web, with their forward ends c² reduced to engage in the recesses or hollows of the fish-plate and their rearward ends in prolongation of the heads provided with cylindrical stems c³, respectively engaging in the orifices $b^4 b^9$ of the walls $b^8 b^8$, while on said stems are mounted springs C², with their forward ends engaging against said heads and their rearward ends against said end walls $b^8 b^8$. Said bolts through the resiliency of said springs are held forwardly in place or the locking-strap B secured in position. At prescribed points passing through said heads are pins c⁴, forming side stops, which engaging against the staple b^5 or the wall b^7 prevent the further forward progress of the bolts as against the resiliency of said springs, and at prescribed points in the forward sides of said stems are formed notches c⁵, to be engaged by the edges of the end walls within said orifices $b^4 b^9$, holding the bolts against the resiliency of the springs in open or unlocked position, while outside of the end walls $b^8 b^8$ the stems are provided sidewise therethrough with pins c⁶, the projecting ends of which by being engaged by the bifurcated ends of a tool C³ serve to withdraw said bolts and bring said notches c⁵ into engagement with said wall edges; but any other suitable tool may be used for withdrawing said bolts.

It will here be remarked that the ends b^2 of the locking-strap B are herein shown and described to differ in their construction, the one, b' , covering the bolt and spring supported thereby, and the other, b^2 , leaving them uncovered; but in practice either form or construction of these ends may be used without changing the character or departing from the spirit of the invention.

The invention having thus been ascertained and described and the manner in which it is performed fully shown and set forth, what is considered new, and desired to be secured by 65 Letters Patent, is—

1. In a nut-lock of the character described, a strap with nut-engaging recesses in its body and having extended ends with offset shoulders having apertures and orifices therein, and headed bolts seated in said apertures and orifices, with springs engaging against the bolt-heads and the outer offset shoulders to removably secure said strap in position, substantially as and for the purpose herein-before set forth. 75

2. In a nut-lock of the character described, a strap with nut-engaging recesses in the body thereof, and having extended ends with bolt-seating apertures and orifices in said ends, and bolts movably seated in said apertures and orifices, with springs provided to forwardly press said bolts, substantially as and for the purpose hereinbefore set forth. 80

3. In a nut-lock of the character described, a strap with nut-holding recesses in its body and having extended ends with angular apertures in their forward portions and circular orifices in their rearward portions, bolts having angular heads seated in said apertures and cylindrical stems seated in said orifices, said bolts movable back and forth, with springs mounted on said stems and engaging between said heads and the end walls of said rearward portions to forwardly press said bolts, substantially as and for the purpose hereinbefore set forth. 95

4. In a nut-lock of the character described, a strap with nut-engaging recesses in its body and having extended ends, with angular apertures at their inner portions and perpendicular walls with circular orifices therein at their outer ends, bolts having angular heads movable back and forth in said apertures, and stems projecting from the heads and movable back and forth in said orifices, with springs mounted on said stems and engaging between said heads and said outer end walls, substantially as and for the purpose herein-before set forth. 105

5. In a nut-lock of the character described, a strap with nut-engaging recesses in its body and having end extensions with angular apertures in their forward portions and perpendicular walls having circular orifices therein at their rearward ends, with bolts having angular heads seated in said apertures and projecting stems seated in said orifices, said bolts movable back and forth, with springs on the stems and engaging between said heads and walls, and with notches therein to be engaged by the edges of said walls within said orifices, substantially as and for the purpose hereinbefore set forth. 115

In testimony whereof we affix our signatures in presence of two witnesses.
